UNITED STATES PATENT OFFICE

171,583

TOLL BOOTH OR SIMILAR ARTICLE

Benjamin Cooper and Stanley Kroll, Brooklyn,
N. Y.; said Kroll assignor to said Cooper

Application August 4, 1953, Serial No. 26,269

Term of patent 14 years

(Cl. D13—1)

To all whom it may concern:

Be it known that we, Benjamin Cooper, a citizen of the United States, residing at Brooklyn, in the county of Kings and State of New York, and Stanley Kroll, a citizen of the United States, residing at Brooklyn, in the county of Kings and State of New York, have invented a new, original, and ornamental Design for a Toll Booth or Similar Article, of which the following is a specification, reference being had to the accompanying drawing, forming part thereof.

In the drawing:

Fig. 1 is a plan view of a toll booth showing our new design;

Fig. 2 is a side elevation of the toll booth;

Fig. 3 is an end view of the toll booth.

We claim:

The ornamental design for a toll booth or similar article, substantially as shown.

BENJAMIN COOPER.
STANLEY KROLL.
